JOHN KRODEL, OF BUTTE, MONTANA.

COMBINATION HINGE AND RACK.

1,208,986.

Specification of Letters Patent. Patented Dec. 19, 1916.

Application filed July 13, 1916. Serial No. 109,120.

To all whom it may concern:

Be it known that I, JOHN KRODEL, a citizen of the United States, residing at Butte, in the county of Silverbow and State of 5 Montana, have invented certain new and useful Improvements in Combination Hinges and Racks, of which the following is a specification.

This invention relates to combination 10 hinges and racks, and more particularly to a door hinge so constructed as to support a coat or towel rack, or the like.

One of the main objects of the invention is to provide a device of the character stated 15 of simple construction and operation.

A further object is to provide a device which can be quickly and easily applied to a door hinge of standard construction.

Further objects will appear from the de- 20 tailed description.

In the drawings: Figure 1 is a side elevation of one form of the invention, Fig. 2 is a similar view of another form of the invention, and Fig. 3 illustrates still another 25 form.

The hinge is of usual construction being composed of two leaves having the intermeshing integral sleeves 1 and 2 pivotally connected by a hinge pin 3. In applying 30 the invention the pin 3 is extended, in the form illustrated in Fig. 2, and a U-bracket 4 provided with integral collars 5 is pivoted on the upper part of this pin. This bracket carries a towel rack 6 secured therein. A 35 spacing sleeve 7 is mounted about the pin below the bottom collar 5 of the towel rack, and rests on a collar 8 integral with a hook 9 and secured to the pin. The hook 9 is provided with an integral supplemental hook 40 10, the vertical arm 10^a of which carries an integral lug 11, the inner face of which is provided with an arcuate recess which fits snugly about the sleeve 2 of the hinge leaf 12 and thus acts to effectively brace the sup- 45 plemental hook 10 and the hook 9. This device may be easily and quickly applied to a hinge of ordinary construction by simply withdrawing the usual hinge pin and inserting instead the elongated pin 13 carrying 50 the rack and hook shown in Fig. 2 of the drawings.

In the device shown in Fig. 3 of the drawings, the hook 9^a is mounted above the upper end of the hinge pin and provided with a

supplemental hook 10^b having a lug 11^a 55 fitting about the hinge sleeve 2^a. In this form of my invention, the towel rack 6 and sleeves 5 and 7 are omitted. In all other respects the form shown in Fig. 3 corresponds to that shown in Fig. 2. 60

In Fig. 1 of the drawings I have omitted the hook entirely and inserted a towel rack provided with a plurality of arms. On the upper end of the hinge pin I mount a collar 7^b carrying an arm 7^c threaded through the 65 upper end of a strap 9^b. The upper end of the strap 9^b is provided with an integral sleeve 9^c mounted about the hinge pin above the hinge proper. At its lower end the strap 9^b is provided with an integral lug 9^b which 70 is secured by a screw 13 to a ring 14 mounted about the hinge pin between the sleeves 15 and 15^a of the hinge leaf 16. The strap 9^b is further provided with an integral 75 downwardly projecting arm carrying a re- cessed head 17 in vertical alignment with a similar head 18 carried by the arm 7^c. A pin is carried by the heads 17 and 18 and a plurality of sleeves 19 are loosely mounted on this pin, each sleeve carrying a rod 20, 80 the whole constituting a multiple arm towel rack.

By invention I have produced a rack which can be readily and easily applied to the hinge of a door and which is especially 85 adapted for use in lavatories and other public places, although it is equally well adapted for use in private houses.

It will be evident that certain changes can be made in the details of the construction and arrangement of my invention without departing from the field and scope of the same and I intend to include all such variations, as fall within the appended 90 claims in this application in which a preferred form only of the invention is disclosed.

What I claim is:

1. In a device of the character described, the combination of a hinge, an elongated pin carried thereby, and a hook mounted on said pin and provided with a bracing member engaging the hinge. 100
2. In a device of the character described, the combination of a hinge, a pin carried 105 thereby and projecting beyond the body of the hinge, and a hook pivotally mounted on said pin and provided with an integral lug

adapted to bear against the body of the hinge for bracing purposes.

3. In a device of the character described, the combination of a hinge, a pin carried thereby and projecting beyond the body of said hinge, a hook mounted on said pin, and a rack mounted on the pin above said hook.

In testimony whereof I affix my signature in presence of two witnesses.

JOHN KRODEL.

Witnesses:

DONALD MOORE,
LEO BUTLER.
